UNITED STATES PATENT OFFICE.

BENJAMIN GOLDSTEIN AND SALVATORE MASTRARRIGO, OF NEW YORK, N. Y., AS-SIGNORS TO JOSEPH ARALE, SALVATORE MASTRARRIGO, AND BENJAMIN GOLDSTEIN, ALL OF NEW YORK, N. Y., COPARTNERS DOING BUSINESS AS BEN & SALLY, OF NEW YORK, N. Y.

BALLET SLIPPER.

Application filed May 9, 1924. Serial No. 711,897.

To all whom it may concern:

Be it known that we, BENJAMIN GOLDSTEIN and SALVATORE MASTRARRIGO, citizens of the United States, and residents, respectively, of New York city, in the county of Bronx and State of New York, and of New York city, in the county of New York and State of New York, have invented certain new and useful Improvements in Ballet Slippers, of which the following is a specification.

The conventional type of ballet slipper used by toe dancers is formed with a relatively stiff or substantially rigidly reenforced toe portion, usually extending well forwardly of the sole of the slipper and sustaining the weight of the dancer. This reinforced portion substantially encircles the forward end of the dancer's foot. The comparatively stiff toe portion causes a very audible and quite undesirable tapping noise when dancing on an uncarpeted floor. Furthermore, the shock of impact when the toe strikes the ground is wholly uncushioned and transmitted directly to the dancer. The life of the slippers is comparatively short because the reinforced toe portion quickly wears through the satin or other outer covering of the slipper.

The object of the present invention is to provide a ballet slipper for toe dancers which will overcome all of these disadvantages and discomforts without destroying the attractive appearance of the slipper.

In the preferred embodiment of the invention we utilize a concealed resilient cushioning member in the toe of the shoe, preferably interposed between the shoe cover and the stiff reenforcement. The normal appearance of the slipper is thus retained, noise is eliminated, the life of the shoe prolonged and the danger of slipping minimized.

In the accompanying drawing,

Fig. 1 is a perspective view of a ballet slipper constructed in accordance with the present invention;

Fig. 2 is an enlarged fragmentary diagrammatic vertical section through the forward end of the slipper; and

Fig. 3 is a fragmentary plan view of a section of lining showing the manner in

which the resilient cushioning pad is attached.

The slipper which we have shown is preferably formed with a soft outer cover 10, usually of satin or some similar material which is attractive in appearance and whose wearing qualities are good. Two thicknesses of lining material 11, 12, are used inside of the outer cover and are preferably secured to the outer cover at the upper edge of the slipper by a binding strip 13. They may be further secured by sewing at 14 just below the binding strip. It will be noted that the toe portion of the shoe projects well forwardly beyond the sole 15 and the insole 16. The sole and the insole are usually of leather, are highly arched and serve to clamp between them the edges of the material forming the outer cover 10 and the linings 11 and 12. The sole and insole are preferably secured together by nailing, although any convenient manner of attachment which will firmly secure the edges of the linings and the cover might be employed. If desired, the insole may include a metallic arched reenforcement 16^a. Between the linings there are interposed several sheets of reenforcing material 17, usually of heavy canvas. Any number of layers of this reenforcement may be utilized and preferably the edges of these layers are also clamped between the sole and insole. This type of slipper is of the class known as a turned shoe, namely, one which is assembled inside out on a last and then turned. In manufacturing, the various layers of reenforcing material are pasted together, while the slipper is inside out on a last. The slipper is then turned and replaced on the last which retains the toe in proper shape during the drying of the paste. The paste used is of a nature to impart great stiffness to the reinforced toe as it dries, acting almost like a cement on the canvas to insure a very rigid reenforcement.

The slipper as thus far described is of conventional form and may be constructed in any well known manner and the details may be materially altered. In carrying out our invention we employ a cushioning pad, 18, of readily compressible resilient material interposed between the reenforcement 17 and

the outer cover 10, at the toe of the shoe. Preferably the resilient pad is of some spongy material such as ordinary sponge rubber and secured as indicated in Fig. 3, 5 by having one of its edges sewed to the lining member 11. The pad is thus interposed between the lining member 11 and the reenforcement 17 and entirely concealed by the outer cover of the slipper.

10 We have not shown the usual ribbons or straps which serve to firmly secure the slipper upon a wearer's foot. Various expedients may be resorted to in this connection. The pad, 18, directly sustains the weight of 15 a toe dancer, cushioning the shock of impact, eliminating the tapping noise usually incidental to the use of the reenforced toe and considerably prolonging the life of the shoe by protecting the outer cover from the 20 direct grinding and wearing action of the stiff reenforcement.

Although the cushioning means might be of other material than the spongy pad which we have shown, it is desirable that it be 25 readily compressible, as well as resilient, since a relatively hard rubber cushion would not eliminate noise. Furthermore, with a relatively hard cushion the reenforcement might be spaced from the floor to such an 30 extent that there would be a tendency to teeter or wobble in use.

Various changes and alterations might be made in the general form and arrangement of the parts described and numerous materials might be substituted for the springy 35 pad herein shown, without departing from the spirit and scope of the appended claims.

Having thus described our invention, what we claim as new and desire to secure by Letters Patent is:

40 1. A ballet slipper for toe dancing including a substantially rigidly reenforced toe portion and resilient cushioning means associated with such toe portion.

45 2. A ballet slipper for toe dancing including a substantially rigidly reenforced toe portion and a spongy resilient shock absorbing member associated with such toe portion.

50 3. A ballet slipper for toe dancing including a substantially rigidly reenforced toe portion concealed within the outer cover of the slipper and resilient cushioning means interposed between said reenforced toe portion and said cover.

55 4. A ballet slipper for toe dancing, including a substantially rigidly reenforced toe portion concealed within the outer cover of

the shoe and a spongy pad of resilient material interposed between the reenforced toe portion and the cover.

5. A ballet slipper for toe dancing, including a reenforced toe portion, a cover for the shoe, lining material interposed between the cover and the reenforced toe portion, and 60 resilient cushioning means secured to the lining and interposed between the resilient toe portion and the cover.

6. A ballet slipper for toe dancing, including a sole portion terminating short of the 70 forward end of the shoe, a relatively stiff, reenforced toe portion, extending forwardly from the sole and resilient cushioning means associated with such toe portion.

7. A ballet slipper for toe dancing, including a sole portion terminating short of the 75 forward end of the shoe, a relatively stiff, reenforced toe portion, extending forwardly from the sole and resilient cushioning means associated with such toe portion, 80 said cushioning means including a resilient pad concealed by the cover of the shoe.

8. A ballet slipper for toe dancing, including a relatively stiff reenforced toe portion 85 and concealed resilient cushioning means associated with such toe portion.

9. A ballet slipper for toe dancing, including a relatively soft outer cover, inner and 90 outer lining members secured to the cushion, a relatively stiff toe reenforcement between the lining members and a resilient cushioning member interposed between the reenforcement and cover.

10. A ballet slipper for toe dancing, including a relatively soft outer cover, inner and outer lining members secured to the cushion, a relatively stiff toe reenforcement between the lining members and a resilient cushioning member interposed between the reenforcement and cover, said cushioning member comprising a pad of spongy resilient 100 material secured at one edge to the outer lining.

11. A ballet slipper for toe dancing, including an outer cover and a substantially rigidly reenforced toe portion and a relatively soft cushioning pad interposed between the cover and the reenforced toe portion.

Signed at New York, in the county of New York and State of New York, this 7th day of May, A. D. 1924.

BENJAMIN GOLDSTEIN.
SALVATORE MASTRARRIGO.
